(57) **CLAIM**

I claim the ornamental design for an extended headrail and track profile, as shown and described.

DESCRIPTION

FIG. 1 is an isometric view looking downwardly at a top and front of extended headrail and track profile of the present invention;

FIG. 2 is a top plan view of the extended headrail and track profile;

FIG. 3 is an end view of the extended headrail and track profile, the other end being a mirror image thereof;

FIG. 4 is a front elevation of the extended headrail and track profile;

FIG. 5 is a bottom plan view of the extended headrail and track profile; and,

FIG. 6 is a rear elevation of the extended headrail and track profile.
